ALUMINUM DECK PLANK FOR TRAILERS

Chester Peek, Sioux City, Iowa, assignor to Wilson Trailer Company, Incorporated, a corporation of Iowa

Filed Nov. 19, 1964, Ser. No. 82,697

Term of patent 14 years

(Cl. D13—1)

Fig. 1

Fig. 2

Fig. 3

Fig. 4

FIG. 1 is a top plan view of an aluminum deck plank for trailers showing my new design;

FIG. 2 is a bottom plan view;

FIG. 3 is an end view; and

FIG. 4 is an end view of a modification thereof wherein the difference is in the flanges as shown.

The plank is broken away in the center thereof in FIGS. 1 and 2 to indicate an article of indeterminate length.

I claim:

The ornamental design for an aluminum deck plank for trailers, as shown and described.
